ILLUMINABLE GRIP STRENGTH INDICATOR

Klaus Johannes Ylinen, Frejgatan 13,
Stockholm, Sweden

Filed Dec. 30, 1959, Ser. No. 58,854

Term of patent 14 years

(Cl. D34—5)

Fig. 1 is a side view of an illuminable grip strength indicator, showing my new design.

Fig. 2 is a front view.

Fig. 3 is a top plan view.

I claim:

The ornamental design for an illuminable grip strength indicator, as shown.
